(57) **CLAIM**

I claim the clustered hexagonal surface design for a gaming console skin, as shown and described.

DESCRIPTION

FIG. 1 is a front view of a clustered hexagonal surface design for a gaming console skin.

FIG. 2 is a front perspective view thereof.

FIG. 3 is another front perspective view thereof.

FIG. 4 is a two-point perspective view thereof.

FIG. 5 is another two-point perspective view thereof.

FIG. 6 is a three-point perspective view thereof.

FIG. 7 is a left side view thereof.

FIG. 8 is a left side perspective view thereof.

FIG. 9 is another left side view thereof.

FIG. 10 is a rear view thereof.

FIG. 11 is a rear perspective view thereof.

FIG. 12 is a right-side view thereof.

FIG. 13 is a right perspective view thereof.

FIG. 14 is a top perspective view thereof.

FIG. 15 is a top view thereof; and,

FIG. 16 is a bottom perspective view thereof.
